UNITED STATES PATENT OFFICE

ARTHUR E. PETERS, OF LITTLETON, COLORADO, ASSIGNOR TO INGERSOLL-RAND COMPANY, OF JERSEY CITY, NEW JERSEY, A CORPORATION OF NEW JERSEY

AIR-LINE OILER

Application filed June 16, 1927. Serial No. 199,312.

This invention relates to oiling devices, but more particularly to an air line oiler adapted to be interposed in a pressure fluid supply line leading from a source of pressure fluid supply to a machine intended to be actuated thereby.

The objects of the invention are to insure an adequate and uniform supply of lubricant to fluid actuated machines during the entire period of operation and to prevent frequent interruptions in the operation of such machines for the purpose of introducing lubricant thereto.

Other objects of the invention will hereinafter appear and to all of these ends the invention consists of the combination of elements, features of construction and arrangement of parts substantially as hereinafter described and claimed and illustrated in the accompanying drawing in which is shown a longitudinal sectional elevation of an air line oiler constructed in accordance with the practice of the invention.

Referring more particularly to the drawing, A designates a casing, the interior B of which forms a reservoir for oil. Within the casing A is formed an integral annular wall C having a passageway D therethrough which communicates at its ends with a hose line E leading from a source of pressure fluid supply to a machine to be actuated thereby, as for instance, a rock drill. The passageway D in this instance is in the form of a Venturi meter in which the restricted or throat portion F is preferably located near the downstream end of the passageway D.

Adjacent the restricted portion F and extending therewith is a plug G having a large threaded portion H threaded into a wall J of the casing A. The body portion K of the plug G may be suitably reduced in diameter in order to hold the weight thereof to a minimum.

The innermost end L of the plug G which projects into the restricted portion F of the passageway D is in the form of a nozzle, and has a passage O which communicates with its outermost end with a recess P. Communication between the recess P and the reservoir B is effected through transverse passages Q

in the body K. The passages O and Q and the recess P thus provide direct communication between the reservoir B and the passageway D for conveying lubricant into the passageway wherein it may mingle with the pressure fluid flowing therethrough and be carried by such pressure fluid to the drill.

In order to control the volume of oil flowing from the reservoir B into the passageway D, a needle valve R is disposed in the recess P and has a conical end S which cooperates with a correspondingly shaped wall T in the recess P for regulating the area of the recess P. The needle valve R is threaded throughout a portion of its length as at U to engage threads V in the plug G. Preferably the outer end of the needle valve R is provided with a head W whereby the needle valve R may be manipulated to effect a suitable adjustment thereof.

As will be observed, the wall J of the casing lies at a lower elevation than the top of the casing, thus forming a recess X of a suitable depth to enable the outer end or head W of the needle valve R to lie below the outer surface of the casing. By means of this construction the needle valve R will be accessible from the exterior of the casing for adjustment, and at the same time said needle valve will be protected against contact with irregularities in the surface whereby the casing A is supported and which might otherwise change the position of the valve.

In order to at all times insure an adequate supply of pressure fluid of normal pressure within the casing A to act on the surface of the oil therein, a passage Y is formed in one end of the casing A to lead from the enlarged end of the passageway D to a point near the top of the reservoir B.

To the end that oil may be introduced into the reservoir B in the various positions which the oiler may occupy in practice and thus avoid the necessity of shifting the oiler about for filling purposes, the casing A is provided with a plurality of filling openings Z, only one of which is shown, the position of the other being indicated by one of two filling plugs b which form closures for the openings Z. Preferably screens c are disposed at the

inner ends of the openings Z to prevent the introduction of foreign matter into the oil supply in the reservoir. Preferably one filling opening Z is formed in the top of the casing A and the other in that end of the casing 5 adjacent the passage Y.

The operation of the device is as follows: After the pressure fluid has been admitted into the hose line and the passageway D, a portion thereof will pass through the passage 10 Y into the reservoir B to create a pressure on the surface of the oil. Inasmuch that there exists a pressure differential in the passageway D, that is, between the restricted portion 15 F and the enlarged portion of the passageway adjacent the passage Y while the pressure fluid is in motion, the oil will be forced through the passages Q and O in the plug G into the restricted portion F from whence it 20 will be carried by the pressure fluid through the hose line E to the machine intended to be lubricated.

If at any time it be desired to decrease the amount of oil flowing into the passageway D, 25 the needle valve R may be screwed downwardly somewhat to decrease the space between the point T of the valve and the conical seat S. Conversely, if it be desired to introduce a greater amount of oil into the passageway D the needle valve may be adjusted to increase the space between these elements.

I claim:

1. An air line oiler comprising a casing having an annular wall therethrough dividing 25 the casing into a reservoir for oil and a passageway for pressure fluid, said passageway having a restricted throat portion and being tapered outwardly toward its ends, said casing having an oil passage connecting the restricted throat portion with the reservoir and an air passage affording communication 40 between the reservoir and an enlarged portion of the passageway, and means in the oil passage for controlling the volume of oil delivered 45 from the reservoir into the passageway.

2. An air line oiler comprising a casing having an integral annular wall therethrough dividing the casing into a reservoir for oil and a passageway for pressure fluid, said passageway having a restricted throat portion intermediate its ends and being tapered outwardly toward its ends, a plug in the casing extending into the passageway, said plug having a passage for delivering oil transversely 55 into the passageway, said casing having a passage for conveying pressure fluid from an enlarged end of the passageway into the reservoir, and adjustable means in the plug controlling the volume of oil flowing through 60 the passage in the plug into the passageway.

3. An air line oiler comprising a casing having an integral annular wall therethrough dividing the casing into a reservoir for oil and a passageway for pressure fluid, said passageway having a restricted throat

portion intermediate its ends and being tapered outwardly toward its ends, a plug in the casing extending into the restricted portion, said plug having a passage for conveying oil into the passageway, a passage in one end of the casing conveying pressure fluid from an enlarged end of the passageway into the reservoir, and an adjustable needle valve in the plug controlling the volume of oil flowing through the passage in the plug into the 70 passageway.

4. An air line oiler comprising a casing having an integral annular wall therethrough dividing the casing into a reservoir for oil and a passageway for pressure fluid, 80 said passageway having a restricted intermediate portion and being tapered outwardly towards its ends, a plug in the casing extending into the restricted portion of the passageway and having a passage for conveying oil from the reservoir into the passageway, a passage in one end of the casing conveying pressure fluid from an enlarged end of the passageway into the reservoir, and a needle 85 valve screwed into the plug controlling the 90 passage therein, said needle valve being accessible for adjustment from the exterior of the casing.

In testimony whereof I have signed this specification.
